CLOSURE FOR COLLAPSIBLE TUBES
AND CONTAINERSFrank McLaughlin, Toronto, Ontario, Canada,
assignor, by mesne assignments, to Douglas
Henderson, Toronto, Ontario, Canada

Application June 13, 1935, Serial No. 26,445

4 Claims. (Cl. 221—60)

Collapsible tubes and similar containers such as used for dispensing fluid, semi-fluid or pasty substances, have usually heretofore been provided with either a screw cap which is removed to permit the contents of the container to be discharged, or a cap having a partial rotary movement which in one position covers the discharge opening and in another position exposes the latter. Both of these types of closures are objectionable in that in the one case the cap is left off by the user and in the other case the discharge opening is left exposed, thus permitting the contents of the container adjacent the discharge opening to dry, thus rendering the material unfit for use and making it difficult to force the dry material adjacent the outlet out of the way to obtain the softer and fresher material lower down in the container.

The object of my invention is therefore to devise a closure which will automatically open up to allow the contents to escape when pressure is applied to squeeze together the walls of the container and which will automatically close when the pressure on the container is relieved.

My object may be attained by means of various constructions such as illustrated in the accompanying drawing in which

Fig. 1 is a vertical section of the closure;

Fig. 2 a plan view of the same, the neck portion of the tube being shown in sections; and

Fig. 3 a perspective view of the valve member.

In the drawing like numerals of reference indicate corresponding parts in the different figures.

Referring to Figs. 1 and 2, 1 indicates the top of a collapsible tube or container having the extension 2 at its upper end in the upper wall of which extension is provided the outlet 3, normally closed by a valve member 4.

The neck or extension 2 of the tube is formed with a central annular flange 8, forming an annular recess between which extend spaced annular flanges 9 on the under side of an annular plunger 10 which carries, by means of the spaced legs 4^a, the valve 4. The spring 5 is positioned between the plunger and bottom of the recess and tends to raise the plunger to seat the valve. When the tube is squeezed the contents pass up the centre of the flange 8 through the central hole of the plunger and between the spaced legs 4^a and exert a downward pressure on the annular plunger to unseat the valve. When squeezing

of the tube is stopped the spring returns the valve to seated position.

What I claim as my invention is:—

1. A collapsible tube or container having a neck portion provided with a central opening in the top thereof; an annular shoulder formed at the lower end of said neck having an upwardly directed annular recess; a valve for said central opening; an annular plunger movable in the neck portion above the annular shoulder; spaced legs connecting said valve and plunger; an annular flange on said plunger extending into the recess; and a spring in said recess normally tending to move the plunger to seat the valve.

2. A collapsible tube or container having a neck portion provided with a central opening in the top thereof; an annular shoulder formed at the lower end of said neck having an upwardly directed annular recess; a valve for said central opening; an annular plunger movable in the neck portion above the annular shoulder, spaced legs connecting said valve and plunger; a pair of spaced annular flanges on said plunger extending into the recess; and a spring having one end positioned between said flanges and its other end in said recess normally tending to move the plunger to seat the valve.

3. A collapsible tube or container having a neck portion provided with a central outlet in the top thereof; an annular shoulder formed at the lower end of said neck having an outwardly directed annular recess, an annular plunger movable in said recess, an inwardly movable valve carried by said plunger for controlling said outlet; and resilient means in said recess normally tending to move the plunger to seat the valve.

4. A collapsible tube or container having a neck portion provided with a central outlet in the top thereof; an annular shoulder formed at the lower end of said neck having an outwardly directed annular recess, an annular plunger movable in said recess, an inwardly movable valve for controlling said outlet, means for maintaining said valve in spaced relationship to the plunger, said means being arranged to permit material to pass from the interior of the container to a position above the plunger before passing to the outlet; and resilient means in said recess normally tending to move the plunger to seat the valve.

FRANK McLAUGHLIN.
